UNITED STATES PATENT OFFICE.

ARTEMUS E. HODGDON, OF SPRINGFIELD, MISSOURI.

VALVE.

1,177,864.

Specification of Letters Patent.

Patented Apr. 4, 1916.

Application filed April 4, 1914. Serial No. 829,650.

To all whom it may concern:

Be it known that I, ARTEMUS E. HODGDON, a citizen of the United States, residing at Springfield, in the county of Greene and 5 State of Missouri, have invented a new and useful Valve, of which the following is a specification.

The present invention relates to improvements in valves, the same being especially 10 designed for use as the drifting valve of steam locomotives and also as a pressure reducing valve for steam, air, or other pressure fluid as well, one object of the invention being the provision of a novel structure 15 which will automatically close a main pressure fluid valve and thus reduce the pressure directed for operating purposes when the mechanism controlled thereby is not running at a maximum speed, the present structure 20 being automatic in its action, and especially economizing steam when the same is used as the drifting valve of a locomotive.

A further object of the present invention is the provision of a novel structure including 25 a piston actuated main valve controlled by a piston actuated slide valve so that the pressure fluid used to actuate the piston of the main valve will be led thereto and thereaway from at the proper time.

30 With the foregoing and other objects in view which will appear as the description proceeds, the invention resides in the combination and arrangement of parts and in the details of construction hereinafter described 35 and claimed, it being understood that changes in the precise embodiment of the invention herein disclosed can be made within the scope of what is claimed without departing from the spirit of the invention.

40 In the drawings—Figure 1 is a sectional view through the complete structure with the parts in their normal positions, the main valve being open so that the pressure fluid is free to flow through the casing. Fig. 2 is a similar view with the main valve closed. Fig. 3 is an enlarged section taken on line 45 3—3 of Fig. 2. Fig. 4 is a modified form of slide valve actuating mechanism shown in section.

50 Referring to the drawings, the numeral 1 designates the valve casing which is provided with the inlet pressure directing channel 2 and the outlet pressure directing channel 4 which is in communication with the 55 first channel 2 through the main valve port 3. A valve 5, which is the main valve, is

disposed above the port 3 to open and close said port, the same being a cylindrical valve provided with a concentric lower socket 6 for the sliding reception of the upstanding pin 7 which is carried by the adjusting screw 8 carried by the casing below the port 3.

A piston 9 is disposed above and connected to the valve 5 and works in the reduced portion 10 of a cylinder 10' fitted in the casing 1 to prevent the pressure reaching the underside of a piston 13 disposed for sliding movement in the enlarged portion 11 of the cylinder 10'. The cylinder 10' is fitted in a vertical bore with which the casing 1 is provided above the channel 4, and a plug 14 is threaded into the upper end of said bore to hold the cylinder 10' therein. The plug 14 has a port 15 normally closed by a plug 15'. The cylinder 10' has a port 50 leading to the atmosphere and located adjacent the shoulder between the portions 10 and 11. The pistons 9 and 13 and valve 5 are preferably integral, they being carried by a reduced portion or rod 12, and the piston 13 is of larger diameter than the piston 9 so that the valve 5 will not be balanced.

The casing has a port 16 led from the pressure fluid directing channel 2 intermediate of its inlet end and the port 3, and said port opens into the lower end of a vertical chamber 17 with which the casing is provided and the casing has an exhaust port 18 leading from the chamber 17 and a pressure fluid directing passage 19 establishing communication between the chamber 17 and the upper end of the cylinder 10' above the piston 13. By this means it will be seen that the pressure fluid directed through the port 16 will enter the passage 19 and thus depress the plunger or piston 13 so as to cause the valve 5 to assume the closed position, as illustrated in Fig. 2.

A combined pressure actuated plunger and stem 20 is mounted for sliding movement 100 through the packing rings 21 which are suitably mounted within the detachable upstanding casing 23 whose threaded end or plug 24 is engaged to the casing 1 in the upper end of the chamber 17. A coiled spring 25 is mounted to compress the packing rings 21 while a disk 26 seals the upper end of the chamber 17 adjacent the plug 24 and also maintains the spring 25 in proper place.

The stem 20 is reduced at its lower end 110 within the chamber 17 to provide the shoul-

der 28 at the end and the shoulder 29 so that the valve member 30 may be properly positioned thereupon and carried thereby in its vertical movement within the chamber 17. 5 Under normal pressure conditions, the valve 30 assumes the upward position, as shown in Fig. 1, at which time the port 18 and passage 19 are in communication by way of the by-pass 33 of the valve 30 and the valve 5 10 is elevated so that the pressure fluid will flow directly from the channel 2 into the channel 4. The valve 30 is provided with the segmental head 32, whose outer curved face is recessed to form the by-pass 33, and 15 the valve 30 will close the port 18 from the chamber 17 and open the passage 19 to such chamber when the parts are in the position as shown in Fig. 2. The valve 30 is slotted as at 31 between the wings 31^a so that the 20 same will fit astride the reduced portion 27 of the stem 20 and yet permit the passage of pressure fluid at each side of the wings 31^a to the upper end of the chamber 17. Two pins 34 which are adjustably mounted in 25 one side of the casing project in the chamber 17 and into the slot 31, so that the valve 30 is permitted a vertical, but prevented from any rotary movement.

In the upper end of the casing or cylinder 30 23 is provided a chamber 35 in which is mounted for reciprocation, a piston 36 connected to and carried by the stem 20, a plug 37 being threaded into the upper end of the casing 23 and provided with a port 38 which 35 is in communication through the pipe 39 and port 40 with the outlet of the channel 4 of the main casing. Pressure fluid is directed into the upper end of the chamber 35 to depress the piston 36 to cause the valve 30 to 40 assume the position as shown in Fig. 2, at which time the pressure fluid from the channel 2 is directed through the port 16 and the chamber 17 into the passage 19 above the piston 13, such action depressing the piston 13 and causing the valve 5 to seat over and close the port 3. This action takes place 45 when the mechanism to which the pressure is supplied from the channel 4 is at rest and therefore there is an accumulation of pressure in such channel 4. As soon as this condition is relieved, however, the piston 36 is elevated to seat against the apertured seat 41^a carried by the plug 38. The casing 23 has a by-pass 41 extending downwardly 50 from the plug 37 a limited distance. Thus, when the piston 36 is raised, the lower face thereof passes slightly above the lower end of the by-pass 41, and this allows the pressure fluid to pass below the piston 36 to normally prevent the operation thereof, but should the pressure be increased by the sudden accumulation of the pressure in the channel 4, the piston 36 will be forced downwardly by the pressure of the fluid flowing 55 through the port 38 against the piston di-

rectly. The by-pass 41 thus renders the piston 36 less sensitive during ordinary conditions, than would be the case without the by-pass, and this prevents the operation of the valve 30 unless the pressure within the channel 14 is increased an abnormal amount. Various means may be provided for returning the piston 36 to raised position when the excessive pressure is relieved, for example, the air below the piston 36 within the chamber 35 can be compressed by the downward movement of the piston, so that when the excessive pressure is relieved, the air in expanding will return the piston 36 to normal position. If the device is in an inverted position from that shown in Figs. 1 and 2, the piston 36 and valve 30 will gravitate to normal position, although this can be accomplished by means of a spring or in various other manners, which need not be illustrated or described in detail, a spring means, however, being illustrated in Fig. 4.

In the structure shown in Fig. 4, the casing 23' which corresponds to the casing 23, carries the stem 20' which in turn carries the slide valve 30', a longitudinal chamber 42 being provided in which is disposed a spring 43 whose lower terminal abuts the shouldered portion 44 and whose upper terminal abuts the under side of the piston 36'. As soon as the pressure is relieved from above the piston, the spring will thus cause the valve 30' to assume the position, as shown in Fig. 1, the plug 37' with its port 38' being provided in this case to permit the direction of the pressure fluid above the piston 36'. The packing glands 21' and the spring 25' are employed as well as the disk 26', all of which correspond to the numerals 90 95 100 105 110 115 120 125 130 135 140 145 150 155 160 165 170 175 180 185 channels, a port between them, a cylinder, a chamber, a port establishing communication between one end of said chamber and the inlet channel, an exhaust port communicating with said chamber, and a passage establishing communication between said chamber and said cylinder, a piston working in said cylinder and having a valve controlling the first mentioned port, a plug closing the cylinder, a member having a plug at one end engaged within the other end of said chamber and having a chamber therein, a piston working within the second mentioned chamber, a stem attached to the second mentioned piston and sliding through said member and projecting into the first mentioned chamber, an apertured plug closing the second men-

tioned chamber, a pipe connecting the third mentioned plug and outlet channel, and a slide valve connected to said stem and slideable within the first mentioned chamber, said slide valve having a by-pass to establish communication between the exhaust port and said passage, and said member having a groove extending from the third mentioned plug past the second mentioned piston when it is adjacent said plug.

In testimony that I claim the foregoing as my own, I have hereto affixed my signature in the presence of two witnesses.

ARTEMUS E. HODGDON.
